UNITED STATES PATENT OFFICE.

WARREN M. BRINKERHOFF, OF AUBURN, NEW YORK.

DESIGN FOR A FIRE-BRICK.

SPECIFICATION forming part of Design No. 33,601, dated November 20, 1900.

Application filed October 25, 1900. Serial No. 34,397. Term of patent 14 years.

To all whom it may concern:

Be it known that I, WARREN M. BRINKERHOFF, a citizen of the United States, residing at Auburn, in the county of Cayuga and State of New York, have invented and produced a new and original Design for Fire-Brick; and I do hereby declare the following to be a full, clear, and exact description of the same, reference being had to the accompanying drawings, forming a part thereof.

My invention is a design for fire-bricks; and it consists in the novel shape and configuration of such brick, illustrated in the accompanying drawings and fully disclosed in the following description and claim.

In the accompanying drawings, which form part of this specification, Figure 1 represents a perspective view of a fire-brick embodying my design. Fig. 2 represents a central transverse section of the brick. Fig. 3 represents a central longitudinal section of the same.

In the drawings, A represents the brick, hav-

ing a face a, provided with the groove or channel a' and a recess a² in the line of the groove.

The leading feature of my design consists of a brick having its rear face a provided with a channel extending centrally throughout its length, with portions of said channel diverging toward the front face b, forming recess a². The diameter of said recess a² in the plane of the face a is greater than the thickness of the brick in a direction perpendicular to the face a.

What I claim, and desire to secure by Letters Patent, is—

The design for a fire-brick, substantially as herein shown and described.

In testimony whereof I affix my signature in presence of two witnesses.

WARREN M. BRINKERHOFF.
